Des. 188,989
Patented Oct. 11, 1960

188,989

COMBINED BANK AND PICTURE FRAME

Ernest J. Swimmer, 229 E. 53rd St., New York, N.Y.

Filed Oct. 2, 1959, Ser. No. 57,776

Term of patent 7 years

(Cl. D34—5)

FIG. 2

FIG. 4

FIG. 3

FIG. 1

FIG. 5

Fig. 1 is a perspective view of combined bank and picture frame showing my new design in an open position;

Fig. 2 is a front elevational view with the frame closed;

Fig. 3 is a top plan view;

Fig. 4 is a side elevational view looking at the hinged side; and

Fig. 5 is a view in elevation, showing the back of the design article.

I claim:

The ornamental design for a combined bank and picture frame, as shown.
